UNITED STATES PATENT OFFICE.

WALTER S. RAE AND ROBERT B. REYNOLDS, OF PITTSBURGH, AND VICTOR BAILEY, OF SWISSVALE, PENNSYLVANIA, ASSIGNEES TO FEDERAL LABORATORIES, INCORPORATED, OF PITTSBURGH, PENNSYLVANIA, A CORPORATION OF PENNSYLVANIA.

HAND WEAPON.

Application filed February 17, 1926. Serial No. 38,788.

This invention relates to hand weapons, and particularly to a weapon which is effective for emitting an incapacitating gas such as tear gas, sneeze gas or the like.

5 In Patent No. 1,567,659 to Ruben B. Lawrence dated December 29, 1925, there is shown a hand weapon comprising a policeman's mace in which is placed a means for emitting an incapacitating gas. In the Lawrence structure, there is shown a trigger mechanism for setting the gas generator into action. We provide an electrically operated gas generator which may be readily tested. These weapons are generally supplied to police forces, and it is extremely important to know that they are always in working condition.

With our improved weapon, tests may be very quickly made to determine whether or 20 not the weapon is in condition for immediate use. These tests are made by using a small lamp to test the battery which is provided for setting off the weapon and, of course, the battery may be very quickly replaced if it is found to be defective or expended.

We further provide an improved cartridge for use in this weapon, the cartridge comprising a foraminous container having a gas 30 producing combustible mixture therein, and having a starter composition covering the container. Preferably a protective covering is put over the starting composition. This cartridge may be readily handled without 35 harm and it may be stored for an indefinite period of time without deterioration.

In the accompanying drawings, illustrating the present preferred embodiment of our invention:

40 Figure 1 is a central longitudinal section through a policeman's mace embodying the invention;

Figure 2 is a side elevation, partly broken away, of the cartridge used, and

45 Figure 3 is a transverse section taken on the line III—III.

In the illustrated embodiment of our invention, there is shown a policeman's club having a tubular body 2 with a flanged end 50 portion 3. The body is covered with leather rings 4, which are compressed against the flange 3 and held in place by a collar 5, which is threaded onto the other end of the body. The body is interiorly threaded

adjacent the end portion 3 to receive a head 55 6, which is also covered with leather 7. The head 6 is provided with a nozzle 8 for directing the incapacitating gas which issues from the mace when it is put into operation.

A handle 9 is threaded onto the other 60 end of the body portion 2 and the entire gas generating mechanism is carried by this handle. The handle is interiorly threaded to receive a plug 10, in which is mounted an insulating block 11.

The insulating block is provided with two contact members 12 and 13 which are made of brass or other suitable metal, and which are drilled to receive the terminals of an electrically operated gas cartridge.

The cartridge is shown in detail in Figure 2, and consists of a base block 14 of hard rubber or other suitable insulating material mounted in one end of a foraminous container 15. This container is cylindrical in 75 shape and is filled with a suitable gas producing mixture, preferably a mixture of chloracetophenone and gun powder is used. A small quantity of suitable stabilizer such as magnesium oxide is also included in the 80 mix. Chloracetophenone is a crystalline substance which vaporizes upon the application of heat and produces a very effective lachrymatory gas. The gun powder acts as a combustible to supply the necessary heat.

A pair of terminal plugs 16 is provided, these plugs fitting into the holes in the members 12 and 13. The plugs extend through the block 14 and are connected to the terminals 17 of a squib 18. The squib comprises 85 a body in which the terminals 17 are secured, a platinum bridge wire 19 and a ball 20 of suitable booster mix. The bridge wire 19 provides sufficient resistance to the flow of electric current so that it becomes heated 90 and fires the ball 20, thus igniting the entire gas cartridge.

It is desired in apparatus of this type to secure a very high concentration of gas and for this reason it is most desirable that the combustion of the material within the cartridge proceed at a high rate. We, therefore, provide a booster composition 21 over the entire outer surface of the foraminous container 15. As soon as the flame, which is 100 initiated at the booster ball 20, reaches the outer surface of the cartridge, it travels with 105 extreme rapidity along the surface by rea-

son of the presence of the booster mix 21, and thus ignites the entire surface of the cartridge. The rapid flame propagation is not the only advantage of the booster mix 21, 5 as it is also effective for causing the gas producing mixture to burn from the outside of the cartridge toward the center, thus doing away with any possibility of the material being blown out with the issuing 10 gases in an unburned condition.

In order that the cartridge may be handled without injury and also in order to permit of its being stored without deterioration, we provide a covering over the entire 15 cartridge. This covering preferably consists of a tissue paper wrapping 22 immediately over a booster mix 21 and an outer shell 23 of celluloid or other combustible material. The cover protects the entire cartridge from moisture and other outside 20 conditions, but is so inflammable that it does not interfere with the action of the booster coating 21. The end of the cartridge remote from the body 14 is covered by a brass 25 cap 24 which fits over the celluloid casing.

The cartridge is shown in its position in Fig. 1. As above stated, the terminal plug 16 fits into the terminal members 12 and 13 and the body 2 may then be screwed into 30 the body 9 to enclose the cartridge in the club. A pin 25 is provided in the body for holding the cartridge in place.

The handle 9 contains an electric cell 26, one terminal 27 of which is adapted to contact with the terminal member 12. The cell is very small and easily fits into a handle. 35 It is of the type generally used in flash-lights and it has been found exceedingly satisfactory in actual operation. As is well known, the other terminal of a flash-light cell is the base or side wall of such cell. We provide a cap 28 which is threaded into the 40 end of the handle 9 and is provided with a copper spring 29 for bearing against the bottom of the cell 26. This not only electrically connects the cell with the handle proper, but also insures proper contact between the terminals 12 and 27.

The switch mechanism by which the electrical circuit is completed is best shown in Fig. 3. It comprises a switch button 30 slidably mounted in a bushing 31 which is threaded in the handle 9 and normally held in the position of Fig. 3 by a leaf spring 32. When the button 30 is depressed, the leaf 50 spring 32 bears against the terminal 13, thus completing the electric circuit and permitting current to flow through the bridge wire 19. When this occurs, the cartridge is set 55 off and a stream of gas issues from the nozzle 8, continuing until the cartridge is expended. A safety 33 is provided, it being merely a slide piece carried by rivets 34 and 60 having tongues adapted to engage a groove 35 in the push button 30. Obviously the

button cannot be depressed until the safety has been withdrawn.

The expended cartridge may be readily removed by unscrewing the body 2 from the handle 9, and the battery may be renewed. 70 if desired, by unscrewing the cap 28. Since the cartridge which we provide is not subject to deterioration, the only part of the weapon which needs testing is the battery, and this may be readily done by removing 75 the battery from the club and testing it with an ordinary flash-light bulb. If the bulb burns, it is known that the battery is in proper condition for igniting the cartridge when desired, and this feature of our invention is particularly useful in cases where 80 the weapon is issued to a large body of men, such as a police force, as in this case it is usually desired to periodically test all of the weapons in service.

The mace may be used in its ordinary manner without the gas producing mechanism being affected in any way, and it makes an extremely convenient and desirable 85 weapon for armed forces. The weapon does not present any unusual appearance and is provided with the ordinary hand strap 36, so that it may be conveniently carried.

It will be understood that the term "in- 90 capacitating gas", as herein used, relates not only to tear gas, but also to other incapacitating gases and smokes. The term "gun powder" is also used as a word of definition, rather than of limitation, and is intended to cover other combustible capable 95 of self-supporting combustion.

While we have illustrated a preferred 100 embodiment of the invention, it will be understood that it is not restricted to the form shown as it may be otherwise embodied 105 within the scope of the following claims.

We claim:—

1. A weapon including a gas generator, an electrical means for setting the same into 110 operation, the gas generator comprising a foraminous container having a combustible incapacitating gas producing mixture therein, and a booster composition over the outside of the container.

2. A weapon including a gas generator, means for setting the same into operation, the gas generator comprising a foraminous container having a combustible incapacitating gas producing mixture therein, and a booster composition over the outside of the 120 container.

3. A weapon including a gas generator, means for setting the same into operation, the gas generator comprising a foraminous container having a combustible incapacitating gas producing mixture therein, a booster composition over the outside of the container, and an outer protective covering over 125 the booster composition.

4. A gas generating unit comprising a 130

- foraminous container having a combustible incapacitating gas producing mixture therein, and a booster composition over the outside of the container.
5. A gas generating unit comprising a foraminous container having a combustible incapacitating gas producing mixture therein, a booster composition over the outside of the container, and an outer protective covering over the booster composition.
10. A gas generating unit comprising a foraminous container having a combustible incapacitating gas producing mixture therein, a booster composition over the outside of the container, and a moisture-proof covering over the booster composition.
15. A gas generating unit comprising a foraminous container having a combustible incapacitating gas producing mixture therein, a booster composition over the outside of the container, and a celluloid covering over the booster composition.
20. A gas generating unit comprising a foraminous container having a combustible incapacitating gas producing mixture therein, a booster composition over the outside of the container, and a protective covering over the booster composition, the protective covering being of inflammable material.
25. incapacitating gas producing means within the container for igniting the mixture, and a booster composition over the outside of the container.
30. 9. A gas generating unit comprising a foraminous container having a combustible incapacitating gas producing means within the container for igniting the mixture, a booster composition over the outside of the container, and a protective covering over the booster composition.
35. 10. A gas generating unit comprising a foraminous container having a combustible incapacitating gas producing means within the container for igniting the mixture, a booster composition over the outside of the container, and a protective covering over the booster composition, the protective covering being of inflammable material.

In testimony whereof we have hereunto set our hands.
